AIR CONDITIONING APPARATUS

Edward S. Lea, Morrisville, Pa., assignor to
George Von Seebeck, trustee, New York, N. Y.

Application August 27, 1936, Serial No. 98,113

1 Claim. (Cl. 62—6)

My present invention, considered from one aspect, is concerned with improvements in air conditioning methods and apparatus and particularly with improvements in apparatus of the general 5 character disclosed in my copending application Serial No. 37,847, filed August 26, 1935.

Considered from another aspect the invention may have a wide and varied range of usefulness in connection with the control of refrigerating 10 apparatus regardless of the purpose for which such apparatus may be used.

In my earlier application above identified I disclose a compact air conditioning machine through which the air to be conditioned is drawn. The 15 air is subjected first to the action of a coarse washing spray and then passed through a mist filled region to humidify it and then subjected to a swirling action to centrifugally eliminate excess moisture. I also disclose a cooling coil in the tank from which the spray water is drawn, refrigerant from this coil being passed through a 20 heat exchanger coil arranged beyond the mist filled region and near the outlet of the machine. This second coil was intended to serve the two-fold purpose of additionally cooling the air leaving the machine and super-heating the refrigerant before it passed back to the compressor, thereby 25 avoiding frosting of the pipe leading back to the compressor.

30 My present invention is concerned with the provision of a control mechanism for obtaining the most efficient results from the general type of machine above described, although the principles involved have a wider field of usefulness.

35 In accordance with the present invention I preferably place a thermostatic valve in the refrigerant line itself where it is not exposed to variations in air temperature. Preferably also I place this control valve (which regulates the admission of refrigerant through the expansion 40 valve into the water cooling coil) at such a position in the heat exchanger near the outlet of the machine that part of the heat exchanger cooling unit acts primarily to additionally cool 45 the air passing through it and part of the heat exchanger acts to superheat the refrigerant passing back to the compressor so that only thoroughly dry refrigerant is returned to the compressor.

50 Cooling coils in air conditioning machines have heretofore proven generally objectionable unless they were either constantly sprayed with water or immersed in a swirling bath of water particularly in cases where these coils were provided 55 with fins which would sweat and upon which dirt

and dust might collect. In the present case the heat exchanger which is provided near the outlet of the machine preferably includes a series of finned pipes. Since however the only air which passes over it has been thoroughly washed before 5 reaching the heat exchanger, it contains no dust or dirt which might deposit thereon.

Preferably the heat exchanger consists of three headers, an inlet header into which gas from the spray water cooling coil flows, an intermediate 10 header which receives the gas after it has served to additionally cool the air leaving the outlet of the machine and a third header receiving substantially dry gas through a series of pipes from the intermediate header and from which the dry 15 gas is withdrawn and returned to the compressor.

My improved control valve which may itself be of standard construction, and is enclosed in a gas and water tight casing, is located in the intermediate header and is directly responsive to 20 the temperature of the refrigerant in such header, this valve regulating in conventional fashion the admission of refrigerant through an expansion valve into the spray water cooling coil.

25 Thus one portion of the heat exchanger serves primarily as an additional cooling means for the air leaving the machine, and the other portion or section thereof serves primarily as a super-heater 30 for warming up and drying out the refrigerant gas before it leaves the last header for return to the compressor. No wet raw refrigerant gas goes back to the compressor.

I am cognizant of the fact that it is not broadly 35 new to install a thermostatic valve directly in the refrigerant line where it is responsive only to refrigerant temperatures rather than outside temperatures but I believe that my special method of installation and the particular arrangement of coils and control valve may take 40 a wide range of usefulness in connection with various refrigerating problems other than the cooling and dehumidification of air.

The control valve here employed is extremely 45 simple and inexpensive. The heat exchanger in which the valve is mounted is designed for economy of construction and efficiency of operation. The application of the valve to the unit in such a manner that the valve is completely protected 50 against direct heat exchange with either air or water facilitates the convenient mounting of the valve or removal of the valve for adjustment or repair.

Other objects of the invention will be more 55 fully apparent from the following description in

connection with the accompanying drawings wherein,

Fig. 1 is a diagrammatic vertical sectional view through an air conditioning machine embodying 5 the invention.

Fig. 2 is an enlarged side elevational view of the heat exchanger and the control valve which it carries.

Fig. 3 is a plan view of this heat exchanger with 10 part of the intermediate header broken away to show the valve mounting, and,

Fig. 4 is a diagrammatic view of the compressor, the spray water cooling coil showing the connections between the control valve and the 15 expansion valve.

Insofar as the air conditioning machine illustrated herein is concerned, various features of it have been disclosed and claimed in my prior applications notably applications Serial No. 20 20 755,916 filed December 4, 1934, now Patent No. 2,079,574 dated May 4, 1937, and Serial No. 37,847, filed August 26, 1935, and while I have shown the present invention as applied to this 25 general type of machine it is to be understood that it may be applied with equal effectiveness to air conditioning units of various other constructions wherein a refrigerated water spray is used to cool and/or wash and/or dehumidify air passing through the unit.

30 As above noted however, it is particularly advantageous to employ this invention where a heat exchanger in the form of a combined air cooling and refrigerant superheating unit is placed in such a position that only thoroughly washed air 35 traverses its surface.

The general type of air conditioning apparatus illustrated in Fig. 1 embodies my improved control mechanism and my improved heat exchanger unit, the rest of the construction being substantially similar to that illustrated in my prior application Serial No. 755,916 now Patent No. 2,079,574.

40 The machine includes a casing indicated generally at 10 which has an open bottom extending into a tank 11 adapted to receive water to be used for washing and dehumidifying the air passing through the machine. Supported upon the top of the casing 10 and resting on a cushioning ring 12 is a motor base plate 13. This base 45 plate supports an electric motor 14 which drives a shaft 15 extending downwardly into the casing.

The upper portion of the casing provides a volute conduit 16 more fully described in my co-pending application just referred to and at the center of this volute conduit, shaft 15 carries a sirocco fan 17. Below the fan the shaft mounts a slinger unit indicated generally at 18. This unit includes a slinger 19 for delivering a small 55 spray into the fan 17 where it is broken up into a fine mist by the fan, and a lower slinger 20 for throwing a violent washing spray radially into the space between the bottom of the volute passageway 16 and the surface of the water in the 60 tank.

65 Both slingers draw water from a well 21 arranged in the bottom of the tank and into which water flows through a valve 22 thermostatically controlled in any suitable manner as by the push 70 rod 23 operated on by the thermostatically controlled cam 24.

Air enters the machine through the top of an inlet passageway 25, passing through a filter 26 and being drawn through and around a screen 75 27. Screen 27 like the inner screen 28 serves to

break up the spray from the lower slinger 20, the air which is drawn inwardly by the fan 17 being subjected to the action of the spray and then being violently discharged from the fan 17 through the volute conduit 16.

5 In passing through the inner portion of the conduit the air is thoroughly humidified by the mist in the region of the fan and as it leaves the conduit it passes upwardly through an outlet passageway 29 in which is located my improved air 10 cooling and refrigerant super-heating heat exchanger unit designated generally at 30.

A float 31 may control an inlet valve through which water is admitted to the tank. Suspended in any suitable manner from the casing is a coil 15 type evaporator 32, certain coils of which are disposed above the liquid level in the tank and certain coils of which are submerged in the liquid. From the outlet of this evaporator coil refrigerant is conducted through a pipe line 33 20 to the inlet header 34 of the unit 30 the structural details of which will be more fully herein-after described.

In the diagrammatic view of Fig. 4, 35 indicates the thermostatic expansion valve through 25 which refrigerant is admitted to the evaporator 32. 36 represents the compressor which forces refrigerant through the line 37 to the expansion valve 35. 38 represents the outlet header of the unit 30 from which dry refrigerant gas passes 30 through pipe 39 to the compressor 36 and 40 represents the intermediate header of the unit 30 within which is mounted the temperature responsive means indicated generally at 41, and having a bulb 47 which is of the fluid pressure 35 operated type. The pressure within the bulb 47 is controlled by the temperature of the refrigerant in the header 40 and this pressure is communicated directly through a conduit 42 to the operating element of the expansion valve 35. 40 Since the expansion valve and control therefor are entirely conventional no details thereof have been shown.

For economy of space the header 34 is arranged directly above header 38, these headers 45 being horizontally disposed. A downwardly inclining series of parallel finned tubes 43 connect header 34 with the header 40, this header being horizontally disposed at a level intermediate the levels of the headers 34 and 38. A second series of finned parallel tubes 44 lead from the header 40 down to the header 38, these tubes 50 lying under tubes 43.

At one end of the header 40 the latter is in open communication with a sleeve 45 projecting 55 axially of the header and preferably extending beyond the casing 10 of the refrigerating machine. Welded onto this sleeve 45 is one element 46 of a coupling piece which holds the bulb 47 in place. Only the outer cylindrical shell of 60 this bulb has been shown but this shell is secured by the coupling piece 46 and the complementary coupling piece 48 in such a position that the major portion of this shell projects inwardly into the header 40. The tube end 49 which projects from this bulb is merely used for filling the tube 42 and the necessary parts of the thermostatic valve device with the desired gas, tube end 65 49 being then closed and sealed.

In order to fully appreciate the manner in 70 which the bulb 47 and its associated air cooling and refrigerant super-heating unit 30 functions, it is necessary to describe somewhat more fully the operation of the conditioner unit illustrated in Fig. 1.

- In normal operation of the machine the air entering through the inlet 25 is thoroughly washed by the cold water from the spray projected by the slinger 20. The air is also substantially cooled by this spray since the spray water is refrigerated by the coil 32. The air is drawn upwardly into the sirocco fan 17 and projected with a violent swirling motion through the volute 16 and as it leaves the machine it comes into heat 5 exchanger relationship with the heat exchanger unit 30. At the region of the fan thorough humidification is effected by the finely divided mist produced by the delivery of water from the slinger 19 against the fan blades.
- 10 15 If the flow of refrigerant through the expansion valve 35 into the coil 32 is regulated by the temperature of the spray water or regulated by the temperature of the air in any part of the machine, there is no assurance that there will 20 not be either gas blocking in the lower coil 32 or the delivery of raw gas back to the compressor from the heat exchanger. Not only is it necessary to place the thermostatic control valve in some position where it is controlled by the actual 25 temperature of the refrigerant but the particular location of this valve in the refrigerant circuit is of great importance. Were the valves subjected directly to air temperatures the cessation of operation of the machine and the consequent 30 quick rise of the air temperature would result in the expansion valve being opened or closed at too frequent intervals. The same thing would be true if the valve was directly responsive to spray
- water temperature. However, when the refrigerant itself is the medium which directly controls the thermostat, much more efficient control of the refrigerating system is had. Furthermore, the positioning of this valve at the critical point 5 which insures against improper refrigeration by the spray water coil as well as against the return of raw gas to the compressor contributes greatly to the efficiency of the system.
- Various changes and alterations may be made 10 in the general form and arrangement of the parts described without departing from the spirit or scope of the appended claim.
- I claim:
- In an air conditioning device of the character 15 in which air to be conditioned is subjected to a refrigerated water spray, a cooling system including a heat exchanger for cooling the spray water, a second heat exchanger in series with said first heat exchanger and arranged to receive refrigerant therefrom, said second heat exchanger 20 having an evaporator portion and a superheater portion and means directly responsive to the temperature of the refrigerant flowing from said evaporator portion for controlling the flow of 25 refrigerant to said first heat exchanger, and means for circulating the spray cooled air first in heat exchange relation with said superheater portion and then in heat exchange relation with said evaporator portion, whereby to superheat 30 the refrigerant flowing from said second heat exchanger and to additionally cool the air.

EDWARD S. LEA.
